UNITED STATES PATENT OFFICE.

HENRY W. BEACH, OF REDWOOD CITY, CALIFORNIA.

PORTRABLE COMMODE.

1,197,786.

Specification of Letters Patent. Patented Sept. 12, 1916.

Application filed October 25, 1915. Serial No. 57,694.

To all whom it may concern:

Be it known that I, HENRY W. BEACH, a citizen of the United States, residing at Redwood City, in the county of San Mateo and State of California, have invented new and useful Improvements in Portable Commodes, of which the following is a specification.

This invention relates to portable commodes; and has for its object to provide a simplified device of this nature that will be inexpensive to construct, light in weight, readily transportable and adapted to removably receive, and effectually seal, within a soil bucket or vessel and be easily operable to expose the parts for use. Devices of this character heretofore in use have not been easily transportable in a strict sense of the word. That is to say, they have been in the form of chairs and other cumbersome articles of furniture and not of such compact and light construction as to be carried readily about and stored in the manner of a package for convenience in transporting or dumping and cleaning the same. Therefore, in accordance with the foregoing object, I employ a commode comprising an inclosed receptacle of sheet metal construction and of such size as to removably receive a vessel within, a sealing mat removably carried on the open end of the vessel, a removable seat resting upon said mat with its top surface flush with or in a plane above the upper edges of the body portion of the receptacle, a hinged cover for said receptacle normally held closed, by means of a latch, and adapted to engage with resilient devices carried on the seat to compress the same for the purpose of retaining the sealing mat in close engagement with the vessel beneath, and a bail-shaped handle for said cover, by means of which the commode may be easily carried about, said handle being foldable to a countersunk position on the cover to permit the commode to be used also as a bench or seat.

One form which my invention may assume is exemplified in the following description and illustrated in the accompanying drawing, in which—

Figure 1 shows a side elevation, partly in section, of a device embodying my invention. Fig. 2 shows a vertical, central, sectional view of the device illustrated in Fig. 1. Fig. 3 shows a detail of the seat-carrying, resilient means adapted to be com-

pressed by the cover of the receptacle for the purpose of sealing the underlying mat in close engagement with the vessel.

Referring in detail to the drawings, it will be seen that I have shown a commode, comprising a body portion 10, cubical or box-like in shape and constructed of sheet metal. A hinged cover is provided for the receptacle and is held in closed position by means of a spring-pressed latch 12, or other suitable device, whereby the said receptacle is entirely inclosed.

A soil bucket or other vessel 13 is removably fitted within the receptacle, being preferably circular in plan and provided with a handle 13', at one side, normally disposed in one corner of the inclosing receptacle. A sealing mat 14 is fitted, removably, in place on the vessel 13 and has a packing ring 15 of soft material encompassing its circumferential border and is adapted to be seated upon the flaring sides of the open end of the vessel for the purpose of sealing the same.

A seat 16 of the required shape is removably carried normally on the sealing mat 14 in engagement with the packing ring 15, being so positioned, with respect to the inclosing receptacle, that its upper surface normally projects above the upper edges of the body portion 10. A plurality of spring-pressed plungers 17, preferably four in number, is countersunk in said seat, one being stationed adjacent to each corner of the same, as shown in Fig. 3. The heads of these plungers are preferably constructed of rubber to further add to the resiliency of the parts, and in extended position they project above the upper surface of the seat where they will be engaged by the hinged cover 11 as the latter is closed to yieldingly press the seat downwardly into tight engagement with the packing ring on the sealing mat for the purpose of effecting a sealing of the vessel 12.

A bail-shaped handle 18 is provided for the cover 11, being pivoted in the downwardly extending legs of a depressed portion 19 of said cover which lies within the circular opening 20 of the removable seat 16. The depression 19 in said cover is of a size and shape to permit the handle to be folded thereagainst and lie flush with the upper surface of the surrounding portion of the cover, whereby the device may be used as a bench or seat.

The operation of the device described is as follows: Normally, and when not in use, the parts are arranged in the position shown in Fig. 2 where the vessel 12 will be sealed, 5 by reason of the mat 14 and the overlying seat held in close engagement therewith by the closed cover 11. To position the parts for use the mat 14 must first be removed and this is accomplished by means of a 10 knob 21 carried thereon and projecting upwardly within the opening 20 of the overlying seat. The cover being swung open, the operator, by means of the knob 21, removes both the mat 14 and seat 16 and then 15 replaces the seat directly in engagement with the open end of the vessel. In such a position the upper surface of the seat will be substantially in line with the upper edges of the inclosing receptacle.

20 It will be obvious that I have provided a simple and inexpensive commode constructed of a minimum number of parts all readily removable and replaceable for the purpose of dumping or cleaning the commode, and, further, that I provide a device 25 of such lightness of weight as to be easily carried about by means of the handle 18, which handle, being foldable, permits of the use of the commode as a bench or seat when 30 not otherwise in operation. This latter feature is of particular advantage where the commode is used in camping or touring parties as it provides a maximum utility and requires but small space for storage.

35 While I have shown and described but one form of my device, it will be understood, nevertheless, that the same is susceptible of modification and changes in the details of construction may, therefore, be resorted to 40 without departing from the spirit of my invention as disclosed in the appended claims.

Having thus described my invention, what I claim and desire to secure by Letters Patent is—

45 1. A portable commode comprising an in- closed receptacle, a hinged lid thereon, a vessel removably received within said receptacle, a sealing mat removably carried on said vessel, and a removable seat discon- 50 nected from said receptacle and resting upon said mat, said seat having its top surface projecting above the upper edges of the receptacle and held in engagement with said mat by means of the closed lid, and down- 55 wardly projecting side portions on said lid engaging with the sides of the receptacle to conceal the seat.

60 2. A portable commode comprising an in- closed receptacle, a hinged lid thereon, a vessel removably received within said receptacle, a sealing mat removably carried on said vessel, a removable seat resting upon

said mat, and disconnected from the receptacle, said seat having its top surface projecting above the upper edges of the receptacle 65 and held in engagement with said mat by means of the closed lid, and resilient means compressible by said cover to cause said mat to be retained in sealing engagement with the vessel, said lid having down- 70 wardly extending side portions engaging with the receptacle to conceal the seat.

3. A portable commode comprising a sheet metal body portion, a hinged cover thereon, a vessel removably received in said body portion, a sealing mat removably received on said vessel, a seat removably carried on said mat and disconnected from the receptacle, said seat being extended above the top of the receptacle a distance approximating the 80 thickness of the mat, and held in engagement with the mat by means of the closed cover, downwardly extending sides on said cover coöperating with the receptacle to conceal the seat, a bail-shaped handle on said 85 cover, and a latch for retaining the cover in closed position.

4. A portable commode comprising an in- closed receptacle, a hinged lid thereon, a vessel removably received within said receptacle, a sealing mat removably carried on said vessel, a removable seat resting upon said mat having its top surface projecting above the upper edges of the receptacle and held in engagement with said mat by means 90 of the closed lid, and a packing ring carried on said mat engaging the circumferential edges of the vessel and engaged by said seat and means for retaining said cover in closed position with the seat engaging tightly with 95 the packing ring, whereby to seal the vessel.

5. A portable commode comprising an in- closed receptacle, a hinged lid thereon, a vessel removably received within said receptacle, a sealing mat removably carried on 100 said vessel, a removable seat resting upon said mat having its top surface projecting above the upper edges of the receptacle and held in engagement with said mat by means of the closed lid, a packing ring carried on 110 said mat engaging the circumferential edges of the vessel and engaged by said seat, and resilient means on said seat comprising countersunk, spring-pressed plungers com- 115 pressible by the cover to cause said seat to tightly engage the packing ring and seal the mat in position on the vessel.

In testimony whereof I have hereunto set my hand in the presence of two subscribing witnesses.

HENRY W. BEACH.
